UNITED STATES PATENT OFFICE.

ALANSON P. BRUSH, OF DETROIT, MICHIGAN.

GAS-MIXTURE PRODUCER.

1,082,007.

Specification of Letters Patent. Patented Dec. 23, 1913.

Application filed March 21, 1912. Serial No. 685,239.

To all whom it may concern:

Be it known that I, ALANSON P. BRUSH, a citizen of the United States, residing at Detroit, in the county of Wayne and State 5 of Michigan, have invented a certain new and useful Improvement in Gas-Mixture Producers, of which the following is a full, clear, and exact description.

This invention is a gas mixture producer 10 which is intended to perform an important function in adapting an internal combustion engine to be started without cranking. Its specific purpose is to furnish to the cylinders of such an engine, on each induction 15 stroke of a piston, when the engine is allowed to run after the spark is turned off, a constant volume of mixed gases (explosive mixture) of uniform quality, regardless of the variations in partial vacuum conditions to which it may be subjected (as a 20 result, for example, of turning off the spark when the engine is running slow or when it is running fast) whereby the cylinders will be uniformly charged with explosive 25 gases of such volume and quality that when an igniting spark is produced therein the engine will surely start.

The invention as shown is embodied in a 30 device having a mixing chamber whose outlet is to be connected with the engine manifold so that it may be subjected to the varying conditions of partial vacuum produced by the induction strokes of the engine pistons when moving at different velocities. 35 This mixing chamber containing a suction controlled valve by which the size of the outlets from said mixing chamber may be varied, (decreased as the pressure at the outlet passage is reduced, and vice versa) 40 whereby to obtain an approximately uniform pressure or partial vacuum condition within the mixing chamber, said mixing chamber having an air inlet, and a gas inlet of the required relative sizes to supply 45 air and gas in the proper proportions.

In the drawings, Figure 1 is a plan view of the device embodying the invention; and Fig. 2 is a central vertical sectional view thereof.

50 Referring to the parts by letters, A represents a cylinder which, together with its cap B, forms the mixing chamber. This chamber has an annular mixture outlet near its top, said outlet comprising one or more holes a^2 through the side wall. The cap B contains an annular recess in its depending

flange, which forms, when the cap is screwed onto the cylinder an annular mixture passage b . A pipe C is connected with the cap, so as to be in communication with the mixture passage. The outlet pipe contains a valve E which may be closed or opened as required. The cap B has a tubular neck b' , internally threaded near its upper end. This neck below the threaded portion has 60 several lateral holes b^2 through it which serve as air inlets; and the cap has a hole b^3 through it communicating with the tubular neck. 65

D represents a gas valve casing. It is 70 screwed into the neck, is tubular, and has a small hole d through its lower end,—which hole is provided with a ball valve F. The upper end of this tubular casing has a lateral gas inlet port d' with which is connected 75 a small pipe G which is to be led to and connected with some suitable supply of gas. Preferably, it is connected with the acetylene gas tank. The size of this gas inlet port is controlled by a conical valve H 80 which screws through the side of the valve casing.

Within the cylinder A, whose upper end constitutes the mixing chamber is a freely 85 movable but fairly well fitted cylindrical piston valve J, to the upper end of which is connected a rod h which goes up through the air inlet hole b^3 in the cap and into the lower end of the hole d in the valve casing. Under normal conditions, this piston valve rests on the bottom of the casing 90 with its top edge below the lower edge of the annular outlet openings b^2 , and the upper end of this pin lies close to the ball valve referred to. There is a small hole a^3 95 in the bottom of the cylinder A.

In order that this device may be called into action when the outlet pipe C is connected with the engine manifold, the regular engine throttle is closed, and the valve E is 100 opened. The result will be that substantially all of the mixture which will be sucked into the engine cylinders by their pistons will be drawn from this device through the pipe C. The piston valve J is constructed 105 of such weight that when the partial vacuum conditions in the mixing chamber are such as result from a reduction of pressure to one-half pound, more or less, below atmospheric pressure, the valve will be raised far enough 110 to completely lift the ball valve from its seat.

If there be any increase in vacuum in the mixing chamber beyond that which causes the piston valve to lift far enough to open wide the ball valve, there will be a further upward movement of the valve such as will partially close the outlet a^2 . The extent of upward movement will depend on the degree of vacuum above it; and the farther up it moves the more will it close the outlet openings a^2 .

The result of the above described action of the parts under various conditions of use will be that there can never be any great change of vacuum conditions in the mixing chamber, and therefore the quality of the mixture will remain uniform. Moreover, since the size of the discharge openings a^2 are reduced in proportion to the increase of vacuum in pipe C, a substantially constant volume of the mixture will be drawn into said pipe on each induction stroke of an engine piston.

Having described my invention, I claim:

1. In a gas mixture producer, a mixing chamber having an air inlet, a gas inlet, and a mixture outlet, an outlet pipe connected with said mixture outlet, a valve in said mixing chamber adapted to be moved by variations of pressure in said chamber and by said movement to more or less completely close said mixture outlet, a valve for the gas inlet, and means whereby said gas valve is opened by the suction-induced movement of the first named valve.
2. In a gas mixture producer, a mixing chamber having an air inlet, a gas inlet, and a mixture outlet through the side walls of said chamber, an outlet pipe connected with

said mixture outlet, a valve for the gas inlet, a piston valve in said chamber adapted to be raised by a decrease in pressure within said chamber and to progressively close the mixture outlet as it rises, and a rod fixed to said piston valve and adapted to engage with and open the gas inlet valve.

3. In a gas mixture producer, the combination of a cylinder having an air vent in its lower end and having an annular mixture outlet through its side walls, and a cap secured to said cylinder and forming the top thereof, and containing an annular mixture passageway with which the annular outlet port communicates, a discharge pipe connected with said cap and communicating with said passageway, said cap having a hole through its top communicating with the interior of the cylinder and having a tubular neck in which are lateral air inlet passages, a gas valve casing screwing into said neck and containing a port through its lower end which communicates with the interior of said tubular neck and having a gas inlet, and adjustable valve for controlling the size of said inlet, a lift valve for closing the gas outlet of said valve casing, a piston valve within said cylinder, and a rod fixed thereto and extending upward into position to lift the gas valve when the said piston is raised.

In testimony whereof, I hereunto affix my signature in the presence of two witnesses.

ALANSON P. BRUSH.
